fig. 1

Fig. 2

Fig. 3

fig. 4

fig. 5

FIGURE 1 is a side elevational view of a jug with bottle receiving pockets for packaging purposes showing our new design.

FIGURE 2 is a side elevational view thereof taken from the left of FIGURE 1.

FIGURE 3 is a side elevational view thereof taken from the right of FIGURE 1; and

FIGURE 4 is a top plan view thereof.

FIGURE 5 is a fragmentary side elevational view thereof.

The dominant features of our design reside in the portions shown in full lines. The small bottles shown in broken lines are for illustrative purposes only.

We claim:

The ornamental design for a jug with bottle receiving pockets for packaging purposes, substantially as shown and described.
